GAME DEVICE

Thomas J. Haynes, Silver Spring, Md.

Application November 25, 1957, Serial No. 48,634

Term of patent 7 years

(Cl. D34—5)

Fig. 2.

Fig. 1 is a top plan view of the game device; and Fig. 2 is a view taken along line 2—2 of Fig. 1 showing the device partly in section and partly in elevation.

I claim:

The ornamental design for a game device, substantially as shown.
